UNITED STATES PATENT OFFICE

2,262,574

ARTICULATOR

Edward L. Chott, Chicago, Ill., assignor of one-half to Hugo J. Chott, Chicago, Ill.

Application May 6, 1940, Serial No. 333,492

8 Claims. (Cl. 32—32)

This invention relates to dental articulators used in the art of dentures for the purpose of producing artificial dentures or sets of teeth, and the object thereof is to produce a novel and desirable dental articulator for producing and setting the artificial teeth in a wax base in proper relation to each other and testing the same before insertion in the person's mouth and is a continuation in part of my prior application, Serial No. 142,790, filed May 15, 1937, and patented May 7, 1940, No. 2,200,058.

Another object of the invention is to provide a novel, positive and accurate adjusting means for holding the upper denture in proper relation to the lower denture or in alignment therewith in the exact relation or condition as in the mouth of the patient so that the proper fit will be insured.

It is now clearly established that the biting areas of the teeth, taken together, lie along a plane which is the curve of a sphere having a radius of four inches and is known as the occlusal plane. This plane is substantially accurate for approximately 95 per cent of adult human teeth, and in the manufacture of artificial dentures, a templet having this curvature is used in the articulator. As is well known by those skilled in the art, the actual angle of the setting of this plane differs with different people and also the depth of the gums of the upper and lower jaws, respectively. Furthermore, in the art of mechanical dentistry where both upper and lower dentures are to be made, one or the other is customarily complete before the making of the other, and the two are then fitted together and aligned, and in this process many separate steps, including tests and adjustments, are necessary. It is therefore desirable in an articulator that the position of the occlusal plane be carefully determined, and that thereafter, the dentures may be made utilizing the templet as much as may be necessary, and that the initial adjustments be not lost; also, it is necessary that the upper denture mechanism be separated from the lower and replaced without losing the adjustments.

Another object of the invention is therefore to provide a dental articulator which approximates as closely as possible the jaws of the human mouth formation and articulated movement of the lower jaw, as well as means associated therewith to insure that the device when adjusted will be positively retained in adjusted position.

Other objects and advantages will appear and be brought out more fully in the following speci-

fication, reference being had to the accompanying drawing, wherein:

Fig. 1 is a plan view of a dental articulator in accordance with the invention;

Fig. 2 is a side elevation thereof partly in section;

Fig. 3 is a vertical section taken on the line 3—3 of Fig. 1;

Fig. 4 is a vertical section of the upper element taken on the line 4—4 of Fig. 1;

Fig. 5 is an enlarged vertical section taken on the line 5—5 of Fig. 4;

Fig. 6 is a horizontal section taken on the line 6—6 of Fig. 5;

Fig. 7 is a vertical section taken on the line 7—7 of Fig. 5; and

Fig. 8 is a vertical section taken on the line 8—8 of Fig. 1.

Referring more particularly to the drawing, there is shown a dental articulator having a base or lower part 10 from which extends spaced side members or upright posts 11 shown formed integral therewith and connected by an upper cross member 12 having a forwardly inclined upwardly arched or curved central portion 13, the branches of which curve toward the ends thereof. This cross member is provided with a bottom recess 14 at the back and a flat part 15 at the front extending substantially vertically to produce upwardly facing inclined shoulders 16 at the ends of said flat part which is also in the form of a recess. The central portion 13 is provided with a depending lug 17 at the front with its inner face spaced forwardly from the wall of the flat part 15 and with a threaded hole 18 to receive an adjusting screw 19 having a large flat head 20 at the bottom and engaged by a wing nut 21 at the top to hold the screw in adjusted position. The ends of the cross member 12 beyond the side members 11 are provided with side extensions 22 having bearing heads 23 at the ends thereof with upwardly and rearwardly open bearing slots 24 and flat bearing ways 25. A bow spring 26 having a top recess 27 at the center straddles the sides of the lug 17 and fits in the recess 14 against the flat part 15 and rests on the shoulders 16, while the curved ends 28 thereof are normally under tension toward the bearing heads 23.

The top member or bracket of the articulator is designated at 29 and has a plate portion 30 for holding the upper denture the same as the base or lower part 10 holds the lower denture. These dentures usually consist of a wax impression around which plaster is poured, as well as around the upper and lower members to provide a good foundation or support for the wax im-

pressions in the relation intended for the patient. The top member has a central depending lug 31 with a hook 32 extending rearwardly and turned up at its free end to engage the head 20 of the screw 19 and this lug 31 has a horizontally threaded bore 33. Depending axially spaced hubs or lugs 34 are provided beneath the top member 29 and like the lug 31 are preferably formed integral therewith as well as aligned horizontally with the lug 31. The lugs 34 are provided with threaded bores 35 aligned with the bore 33 in horizontal axial relation and at the bottom with vertical threaded bores 36 communicating at the top with the threaded bores 35. A friction locking member 37 is provided at the upper portion of each threaded bore 36 and is preferably in the form of a plug of soft metal such as alloy which is flowed or forced into position by inverting the lugs with the bores 35 or lower ends of the bores 36 closed, as will be later described. Set screws 38 are engaged in the bores 36 to force the locking members or plugs 37 to frictionally engage trunnions or shaft sections 39 at their threaded inner portions 40 which are threaded in the bores 33 and 35. The metal of the locking members or plugs 37 are forced into threads 40, and as the metal of the latter is harder than that of the plugs, the threads 40 will cut into the metal of the plugs, but primarily the plugs will so frictionally engage the threaded portions of the trunnions that the latter will be positively held in adjusted position spaced apart at their inner ends in the bearing lug 31. The trunnions 39 may be turned any suitable way, as by suitable holes 41 in which a key, nail or pin is inserted. The trunnions 39 have reduced bearing portions 42 at their outer ends forming outwardly facing shoulders 43 at the outer ends of the trunnions 39 to engage or lie within the inner sides of the side extensions 22. Manipulating knurled knobs 44 are provided on the ends of the trunnions 39 at their bearing portions 42 and may be in the form of nuts engaged on the threaded ends 45 of said bearing portions. By this means, the lower support or base member, simulating the lower jaw, may be pivoted on the upper support in the same manner as with the lower jaw of the patient and the spring 26 will not only retain the pivot axis of the upper support in position with respect to the lower support and vice versa, but will frictionally hold the same due to the ends 28 of the spring engaging the ends of the trunnions and preventing the displacement of the reduced bearing portions thereof from the slotted bearings 24, although there may be proper condyle and incisular movements of the dentures relatively, as mounted on the upper and lower supports which are capable of such relative movements. Moreover, the trunnions may be adjusted in or out axially horizontally in the threaded lugs 31 and 34 at their threaded bores 33 and 35 merely by releasing the set screws of the locking devices and turning the trunnions by pins inserted in the holes 41 or by means of the knobs 44. The upper and lower supports may be adjusted toward and away from each other and the adjustment maintained by the set screw 19 which may be held by the wing nut 21 so that the extremity of the hook 32 will engage the head 20 thus establishing the proper angular spaced relation between the dentures. The dentures may be shifted sidewise, or laterally with respect to each other by adjusting the trunnions and the shoul-

ders or end portions 43 thereof relative to the inner faces of the upright side extensions or bearings 22. In other words, by adjusting the trunnions oppositely to the inner faces of arms 22, the upper support may be shifted toward one side and vice versa. Thus the articulator may be used for effective testing and setting the alignment of teeth after they have been set up to insure that they are properly aligned to fit the patient and so that the biting and chewing movements may be made in the proper manner. In this way the articulator is used to obtain the necessary adjustments without requiring that the device be applied to the patient and to insure that the grinding operations will produce accurate adjustment so that the dentures will properly fit the person for whom made and so that they will effectively serve their purposes.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to secure by Letters Patent is:

1. In a dental articulator having upper and lower members for supporting dentures, said upper member having depending threaded lugs, trunnions threaded into said lugs and having bearing portions pivotally supported on the other member, and means engaged in the lugs and with the peripheries of the trunnions to hold the same against turning.

2. A dental articulator comprising a lower member with an upstanding portion provided with rearwardly and upwardly open bearings and forwardly inclined ways in rear thereof, an upper member having a central depending lug and a depending lug on each side thereof in spaced relation thereto, all of said lugs having threaded bores in axial alignment, trunnions having threaded inner ends engaged through the second-named lugs and into the first-named lug in spaced relation at their inner ends, said trunnions having reduced outer portions forming shoulders adapted to abut the inner faces of the bearings with the reduced portions pivoted in the bearings, means to hold said trunnions in the bearings and means to adjust the upper member in relation to the lower member.

3. An articulator comprising a base for a lower denture having a pair of upstanding supporting posts, said posts being provided with forwardly and downwardly inclined ways each open at the upper end and terminating at the lower end in semi-cylindrical alined bearings, a top bracket member for the upper denture, said bracket having a transverse threaded bore, a pair of trunnions adapted to normally rest in said semi-cylindrical bearings and each provided with a threaded inner end engaging in said threaded bore whereby the upper bracket may be laterally adjusted relative to the base and resilient means for yieldingly holding said trunnions in said bearings.

4. An articulator comprising a base for a lower denture having a pair of upstanding supporting posts, said posts being provided with forwardly and downwardly inclined ways each open at the upper end and terminating at the lower end in

semi-cylindrical alined bearings, a top bracket member for the upper denture, said bracket having a transverse threaded bore, a pair of trunnions adapted to normally rest in said semi-cylindrical bearings and each provided with a threaded inner end engaging in said threaded bore whereby the upper bracket may be laterally adjusted relative to the base, means on said trunnions adapted to engage the inner ends of said bearings to limit the outward movement of said trunnions, and means on the outer ends of said trunnions to manipulate the bracket.

5. An articulator comprising a base for a lower denture having a pair of upstanding supporting posts, said posts being provided with forwardly and downwardly inclined ways each open at the upper end and terminating at the lower end in semi-cylindrical alined bearings, a cross member connecting said posts adjacent their upper ends, a top bracket member for the upper denture, said bracket having a transverse threaded bore, a pair of trunnions adapted to normally rest in said semi-cylindrical bearings and each provided with a threaded inner end engaging in said threaded bore whereby the upper bracket may be laterally adjusted relative to the base and resilient means carried by said cross member for yieldingly holding said trunnions in said bearings.

6. An articulator comprising a base for a lower denture having a pair of upstanding supporting posts, said posts being provided with forwardly and downwardly inclined ways each open at the upper end and terminating at the lower end in semi-cylindrical alined bearings, an arched cross member connecting said posts adjacent their upper ends, a stop member threaded through said cross member and having an enlarged head on its lower end providing a flat bearing surface substantially parallel with the plane of said inclined ways, a top bracket member for the upper denture, said bracket having a transverse threaded bore, a pair of trunnions adapted to normally rest in said semi-cylindrical bearings and each provided with a threaded inner end engaging in said threaded bore whereby the

upper bracket may be laterally adjusted relative to the base, resilient means for yieldingly holding said trunnions in said bearings, a depending member on said top bracket extending rearwardly and upwardly to engage said head, and means for locking said stop member in adjusted position.

7. An articulator comprising a base for a lower denture having a pair of upstanding supporting posts, said posts being provided with forwardly and downwardly inclined ways each open at the upper end and terminating at the lower end in semi-cylindrical alined bearings, a top bracket member for the upper denture, said bracket having a transverse threaded bore, a pair of trunnions adapted to normally rest in said semi-cylindrical bearings and each provided with a threaded inner end engaging in said threaded bore whereby the upper bracket may be laterally adjusted relative to the base, means for locking said trunnions in adjusted position and resilient means for yieldingly holding said trunnions in said bearings.

8. An articulator comprising a base for a lower denture having a pair of upstanding supporting posts, said posts being provided with forwardly and downwardly inclined ways each open at the upper end and terminating at the lower end in semi-cylindrical alined bearings, an arched cross member connecting said posts adjacent their upper ends, a top bracket member for the upper denture, said bracket having a transverse threaded bore, a pair of trunnions adapted to normally rest in said semi-cylindrical bearings and each provided with a threaded inner end engaging in said threaded bore whereby the upper bracket may be laterally adjusted relative to the base, said arched member being formed with a flat forward face, a bowed spring, lugs on said arched member holding the central portion of said spring against said flat face, and the ends of said spring being recurved to engage said trunnions to yieldingly hold the same in said bearings.

EDWARD L. CHOTT.
